FIG. 3.

UNITED STATES PATENT OFFICE.

JOHN PURDY, OF NEW YORK, N. Y., ASSIGNOR TO THE MONARCH TYPEWRITER COMPANY, OF SYRACUSE, NEW YORK, A CORPORATION OF NEW YORK.

TYPE-WRITING MACHINE.

1,025,644.

Specification of Letters Patent.

Patented May 7, 1912.

Application filed February 8, 1909. Serial No. 476,592.

To all whom it may concern:

Be it known that I, JOHN PURDY, a citizen of the United States, and resident of the borough of Brooklyn, city of New York, 5 in the county of Kings and State of New York, have invented certain new and useful Improvements in Type-Writing Machines, of which the following is a specification.

My invention relates more particularly to 10 card feeding and has for its main object to provide means for properly holding cards against the surface of a cylindrical platen and for feeding the same therewith.

To this end my invention consists in the 15 various features of construction and combinations and arrangements of parts, all as more fully described and particularly pointed out in the appended claims.

In the accompanying drawings, Figure 1 20 is a vertical cross-section, on an enlarged scale, of the carriage and upper portion of the frame-work of a Monarch typewriting machine embodying my invention. Fig. 2 is a similar view with some of the parts 25 omitted and showing certain of the parts illustrated in Fig. 1 in different positions. Fig. 3 is a bottom plan view of the carriage, detached.

In the various views the same parts will 30 be found designated by the same numerals of reference.

1 is the top plate of the machine, 2, supporting posts or brackets for the paper carriage 3, the back bar 4 of which is constructed 35 to coöperate with rollers 5 which also coöperate with grooved rails 6 mounted on said brackets or supports 2. At the ends of the back bar are side or end bars 7, 7^a, which support the platen 8 and platen shaft or rod 9 as usual. The main, rear feed rollers 10 are mounted on a shaft 11 whose ends are supported in depending hanger arms 12 pivotally mounted at 13, in lugs or supports 14 projecting forwardly from the back bar of 45 the carriage. These arms are provided with springs 15 which operate to force the feed rolls 10 toward and against the platen, the deflector or apron 16 being cut away at 17 for passage therethrough of the roller sections 10. The deflector 16 is pivotally mounted upon a rod 18 secured at its ends 50 to the side bars of the carriage frame and

springs 19 tend to keep said deflector against the platen. These springs are shown herein as mounted upon arms 20 pivoted at 21 in 55 the lugs 14. Said arms 20 support at their forward free ends a shaft 22 which carries a set of pressure rollers 23. The deflector 16 is cut away at 24 so that the rollers 23 may contact with the platen. The arms 20 and rollers 23 are pressed toward the platen 60 by springs 25 in the customary manner.

26 designates the usual front platen scale which is pivotally mounted at 27 on the forward ends of arms 28 secured by screws 29 to forwardly projecting lugs 30 on the back bar of the carriage. These arms 28 are provided with flat springs 31 whose free ends bear upon lower, bent portions 32 of the platen scale and thereby force the upper 70 edge of said scale against the platen.

33 designates the usual line finder and pressure device which is pivotally mounted at 34 and by a spring 35 pressed against the front face of the platen. The lower end of 75 the pressure device 33 is curved outwardly as at 36 and is adapted to be acted upon by a vertically movable slide 37, whose function is to increase or diminish the pressure of the upper end of the device 33 against the 80 platen, as may be desired. When the slide is down the pressure is that resulting from the spring 35 alone, but when the slide is pressed up the pressure is increased by the camming action of the slide on the lower 85 end 36 of the pressure device.

The parts thus far described are all in common use on the said Monarch machine and therefore need no further detail description.

The parts now to be described constitute the new features of the construction.

38, 38 are two stiff curved fingers pivotally mounted at their rear ends upon the rod 18. These fingers are held in position 95 lengthwise of said rod by collars 39. The deflector is cut away or slotted at 40 for the accommodation of the fingers 38 and so that they may press against the platen or the card thereupon. These fingers 38 are 100 on the under side of the platen and preferably terminate just in rear of the shaft 22. Means are provided for forcing the fingers 38 firmly against the cards, said means con-

sisting in the present instance of cams or crank arms 41, pinned or otherwise secured to a rock shaft 42, extending lengthwise of and under the platen and mounted in depending brackets 43 fastened on the under side of the end bars 7, 7^a. The rock shaft 42 is adapted to be rocked by means of a lever or arm 44 secured thereto at one end. Normally this arm or lever rests against the hub 45 of one of the platen rotating hand-knobs or wheels 46, and when it is in this position the cams 41 are out of use and the card pressing or clamping fingers 38 are ineffectual to operate on the cards. In the use 10 of this construction, the card is fed into the machine as usual, at the point *x*, between the deflector and the platen and between the feed rollers 10 and the platen, and for this purpose the feed rollers may be cast off 15 as usual, though this is not necessary. When the card has been thus part-way introduced, the lever 44 is thrown rearwardly against a stop pin 47 and the cams, eccentrics or crank arms 41 are caused to rise and 20 lift the pressure fingers 38 and force them hard against the card. When the lever is moved back against its stop 47, the cams will be in the position shown at Fig. 2 and they will be locked thereat by reason of their position in alinement with the platen shaft 25 9 and the rock shaft 42. When the parts are in these positions the card may be fed forwardly to the printing point, either by the hand knobs or line feeding mechanism, 30 the supplemental pressure fingers 38 assisting by their extra pressure the feed movement of the card. These fingers 38 also cause the card to conform accurately to the surface of the cylinder or platen and hence 35 40 the type impressions are much better than otherwise would be the case. It has been found in practice that certain stiff or heavy cards that cannot be properly shaped to the platen and fed around therewith with the ordinary feeding devices may be made to 45 50 conform properly to the surface of the platen and to feed accurately and uniformly with the platen when the extra or auxiliary pressure fingers 38 are employed.

55 It will be observed from Fig. 2 that the shaft 42 is shown in two positions, one in dotted lines and one in full lines. The dotted lines represent the normal position of the shaft and the full lines the position 55 the shaft assumes when the cams are pressing against the fingers 38. The shaft is made purposely thus to bend or flex downwardly so that it may, during the locking of the fingers 38 in working position, simultaneously carry off the feed rolls 23 from contact with the platen, these rolls not being needed when the fingers 38 are in use. In order that the feed rolls 23 may be thus cast off the rod 42 preferably passes through 65 loops or brackets 48 on the arms 20 which

carry the feed rolls 23. When the rolls 23 move away from the platen the deflector drops or moves away also, so that there is no danger of the card being caught in the openings in the deflector.

The devices 38 for conforming or shaping the card to the cylinder and causing it to feed therewith are arranged beneath the cylinder and between the front and back feed rollers and the surfaces of the devices 70 75 38 are smooth so that the card may be dragged thereover as the platen is rotated, the extra pressure of the card against the surface of the cylinder not being great enough to hold the cylinder against turning. By reason of mounting the shaft 42 80 flexibly the devices 38 may yield slightly when a thick card passes over the camming-up devices.

When the leading portion of the card has 85 been fed past the free ends of the fingers 38 it is engaged by the spring pressed platen scale and by the front pressure device 33, so that at times both the devices 38 and 33 are assisting in the feed of the card. When the 90 card has entirely left the devices 38, the device 33 will complete the feed. If desired the usual front paper fingers and small rolls (not shown) may be employed in some cases.

The devices or conformators 38 when not in use hang slightly below the upper surface of the deflector.

It will be seen from the foregoing that the machine is adapted for ordinary correspondence work with paper as well as for card work. When the machine is used for correspondence work the fingers 38 have no pressure against the paper and the ordinary feeding devices are left free to co-act with 100 the platen to feed the paper, while on the other hand when cards are to be written upon the pressure fingers 38 are brought into service and the front feed rolls 22 are thrown out of working position so that they 105 may not in any wise interfere with the feeding of the cards by catching their leading edges.

Various changes may be made without departing from my invention.

What I claim as new and desire to secure by Letters Patent, is:—

1. In a typewriting machine, the combination with a cylindrical platen, of a card pressure device on the under side of the 120 platen and normally inert, and means for pressing said device forcibly against the platen for the card thereon and causing the card to feed with the platen when the latter is rotated.

2. In a typewriting machine, the combination with a cylindrical platen, of a card pressure device arranged on the under side thereof and below the writing line and curved to conform to the surface of said 130

platen, and independent means for at will 50 forcibly pressing said device against the platen or against the card thereon.

3. In a typewriting machine, the combination with a cylindrical platen, of a pivotally mounted card conformator arranged on the under side of the platen and normally inert, and means for forcibly pressing the same against the platen or the card thereon 10 and causing the card to feed with the platen when the latter is rotated.

4. In a typewriting machine, the combination with a cylindrical platen, of a card conformator mounted at one end at the rear 15 side of the platen and extending forwardly under the platen and terminating at the lower front portion thereof, and means for pressing said conformator against the platen or against the card thereon and causing 20 the card to feed with the platen when the latter is rotated.

5. In a typewriting machine, the combination with a cylindrical platen, of a pivotally mounted card conformator arranged on the under 25 side of the platen and below the writing line, and independent hand operated means for pressing said conformator against the platen or the card thereon and causing the card to feed with the platen when the latter 30 is rotated.

6. In a typewriting machine, the combination with a cylindrical platen, of a card conformator arranged on the under side of the platen, a rock shaft, and a cam on said 35 rock shaft for forcing the conformator against the platen or the card thereon.

7. In a typewriting machine, the combination with a cylindrical platen, of a pair 40 of pivotally mounted pressure devices arranged on the under side of the platen and below the writing line and conforming to the surface thereof, and independent means for at will forcibly pressing said devices against the platen or the card thereon.

45 8. In a typewriting machine, the combination with a cylindrical platen, of a deflector on the under side thereof having slots or openings, a card conformator adapted to play in said openings, and means for pressing said conformator against the platen and the card thereon.

50 9. In a typewriting machine, the combination with a cylindrical platen, a deflector on the under side thereof having slots or 55 openings, a pair of pivoted pressure devices adapted to said slots or openings and normally extending below the same, and means for pressing said pressure devices up through said slots or openings and against the platen or the card thereon.

60 10. In a typewriting machine, the combination with a cylindrical platen, a rear pressure roll, and a deflector, of a card conformator arranged on the under side of the

platen, and independent means for at will 65 causing it to press forcibly against the platen or against the card thereon.

11. In a typewriting machine, the combination with a cylindrical platen, of a rear feed roll, a pivotally mounted deflector, and 70 a pivotally mounted card conformator, both said deflector and said conformator being arranged on the under side of the platen and curved in accordance with the surface of the platen.

75 12. In a typewriting machine, the combination with a cylindrical platen, of a rear pressure roll, a deflector, a rod upon which said deflector is pivotally mounted, a card conformator also pivotally mounted upon 80 said rod, said deflector and card conformator being arranged on the under side of the platen, and means for pressing the card conformator against the platen or against the card thereon.

85

13. In a typewriting machine, the combination with a cylindrical platen, of a rear pressure roll, a front pressure roll, a card conformator on the under side of the platen, and means for pressing said conformator 90 against the platen and causing the front pressure roll simultaneously to move away from the platen.

14. In a typewriting machine, the combination with a cylindrical platen, a rear 95 pressure roll, a front pressure roll, and a deflector, of a card conformator on the under side of the platen, cams adapted to press said conformator against the platen, and a yielding shaft on which said cams are 100 mounted, said yielding shaft being operatively connected to the front pressure roll, whereby when the conformator is pressed upwardly the front pressure roll is moved away from the platen.

105

15. In a typewriting machine, the combination with a cylindrical platen, of a rear pressure roll, a front pressure roll, a card conformator on the under side of the platen arranged between said pressure rolls and 110 below the writing line, and means for forcing said conformator against the platen.

16. In a typewriting machine, the combination with a carriage, a cylindrical platen, of a card conformator pivotally 115 mounted on the rear side of the platen and extending under the same, a front pressure roll mounted on pivoted arms, a yielding rock shaft mounted in the side frames of the carriage and passing through connecting devices on said pressure roll arms, and cams on said rock shaft whereby said cams force the conformator against the platen and the yielding shaft forces the pressure roll away from the platen.

120

17. In a typewriting machine, the combination with a cylindrical platen, of a rear pressure roll, a front pressure roll, a paper

125

- scale, a front pressure device, a deflector on the under side of the platen having slots or openings, a pair of curved pressure devices on the under side of the platen adapted to 5 play in said slots or openings in the deflector, and a hand actuated rock shaft arranged under the platen and provided with cams for forcing said curved pressure devices against the platen.
- 10 18. In a typewriting machine, the combination with a cylindrical platen, of a card conformator on the under side thereof, a rock shaft, and cams on said rock shaft for forcing and locking the conformator against 15 the platen.
19. In a typewriting machine, the combination with a cylindrical platen, of a card conformator normally inert, and independent means for at will causing said conformator to press forcibly against the platen or 20 against the card thereon.

Signed at the borough of Manhattan, city of New York, in the county of New York and State of New York, this 6th day of February, A. D. 1909.
